CLAIM

The ornamental design for a yoke, substantially as shown and described.

DESCRIPTION

FIG. 1 is a perspective view of a yoke showing my new design;

FIG. 2 is a top plan view thereof; the bottom plan view being a mirror image thereof;

FIG. 3 is a right side elevation view thereof, which is the same as a left side elevation view;

FIG. 4 is a rear elevation view thereof; and,

FIG. 5 is a front elevation view thereof.

The drawings are stippled to show a contrast.
